UNITED STATES PATENT OFFICE.

WILLIAM T. SMITH, OF PHILADELPHIA, PENNSYLVANIA.

DESIGN FOR A WOVEN FABRIC.

SPECIFICATION forming part of Design No. 22,234, dated February 21, 1893.

Application filed January 26, 1893. Serial No. 459,892. Term of patent 3½ years.

To all whom it may concern:

Be it known that I, WILLIAM T. SMITH, a citizen of the United States, residing at Philadelphia, in the county of Philadelphia and

5 State of Pennsylvania, have invented and produced a new and original Design for a Woven Fabric, of which the following is a specification, reference being had to the accompanying drawing.

10 The leading features of my design are a representation of the landing of Columbus, followed by armed men, Indian tents on the left, partially hidden by tropical plants, a ship shown in the back ground, the whole sur-

rounded by an ornamental scroll and floral border, as shown in the accompanying drawing, which is sufficient to enable others to make and use my invention.

Having as above fully described my invention, what I claim as new, and desire to secure by Letters Patent, is—

The design for a woven fabric, as shown in the accompanying drawing.

W. T. SMITH.
